UNITED STATES PATENT OFFICE.

MILTON HUTCHINS, OF ARLINGTON, MASSACHUSETTS.

TRUSS.

SPECIFICATION forming part of Letters Patent No. 416,001, dated November 26, 1889.

Application filed June 10, 1889. Serial No. 313,688. (No model.)

To all whom it may concern:

Be it known that I, MILTON HUTCHINS, of Arlington Heights, Arlington, in the county of Middlesex and State of Massachusetts, have 5 invented certain new and useful Improvements in Trusses, of which the following is a specification.

The object of my invention is the construction of a truss which will effectually hold the 10 rupture and at the same time be very much easier and convenient to the person wearing it than those now in use.

To these ends my invention comprises, first, an improved pad for operating upon a hernia 15 or similar affection of the body, said pad consisting of a spiral spring, having, when in its normal condition, the form of a frustum of a cone, so that the area or bearing-surface of the pad will be increased in proportion to 20 the extent of compression of the spring; second, an improved truss-supporting pad consisting of a strip of metal or other suitable material supporting two separated pads proper, said supporting-strip being yieldingly 25 connected with the body of the truss, whereby the pad may be arranged to rest upon the back of the wearer and serve in an efficient manner to support the truss in position without bearing on the patient's spine; third, an 30 improved truss as an entirety, consisting of the improved hernial and supporting pads before mentioned and their co-operating connection, all as will be hereinafter more fully described, and pointed out in the appended 35 claim.

Reference is to be had to the annexed drawings, and the figures of reference marked thereon, forming a part of this specification, the same figures designating the same parts, 40 as the case may be, wherever they occur.

In the drawings, Figure 1 is a top plan view of my improved truss complete. Fig. 2 is a face view of the hernial pad and a portion of the body of the truss. Fig. 3 is a central sectional view of Fig. 2.

In carrying out my invention I construct the body 2 of the truss as a spring formed to extend from the back of the wearer around his side or hip to the point where the hernia 50 or other affection exists. Said body 2 may be made of various materials and be constructed

in various ways, that here shown, and which I have found to answer the purpose very well, consisting of flexible wires 4, suitably covered, if desired, with a belt or covering 3, 55 of leather. This combination forms at once a light, strong, and flexible structure, all of which qualities are desirable in truss body or spring.

The hernial pad consists of a spiral spring 60 6, made to resemble, when in its normal position, the form of a frustum of a cone, as shown in Fig. 1, which spring may be provided on its smaller end with a small piece 7, of felt or other soft material, to cover the end of the 65 spring and prevent injury therefrom to the body. The larger end of the spring is attached to the forward end of the truss-body 2 at such point as that when the truss is on the patient the spring when compressed will 70 have a bearing on the hernia or other similar affection. With this construction the hernia is held by a surface formed by the outer sides of the coils of the spring, said surface being flexible and open in its construction, so as to 75 avoid heating, and when strain on the hernia increases and the latter becomes more difficult of holding, the force of pressure and area or extent of bearing-surface of the pad are increased, so that all exigencies of the case are 80 met in accordance with the degree of the same. The spring 6 is so coiled as that when it is compressed each coil will enter and lie within its successor, forming a round and substantially-flat pad, as shown in Fig. 3, the 85 outer or smallest coil being first compressed within the next succeeding coil, and so on, until a part or all of the coils may be compressed.

In some instances I have formed the central protecting-piece 7 of wire or other material than felt, and in some instances have dispensed with said piece altogether.

8 8 designate pads of felt or other suitable material supported on the ends of a flexible 90 strip 9, of metal or other suitable material, which strip is yieldingly connected with the rear portion of the truss spring or body 2, such yielding connection being here shown as consisting of a spiral spring 10, coiled in 95 a manner similar to spring 6, constituting the hernial pad, so that when said spring 10 is 100

compressed the successive coils may be folded within those preceding, and thereby permitting the spring 10 to be brought into compact form and occupy as little space as possible 5 between the strip 9 and the body 2. I do not limit myself to this form of spring, however, as the yielding connection between the strip 9 and body 2, but may use any other suitable form of coiled spring as the yielding connection.

The pads 8, 8 are separated, so that they may rest upon the back of the wearer and not touch or bear upon the patient's spine, thus rendering comfortable the wearing of the 15 truss, and at the same time affording a construction whereby it is securely held in place, the yielding and, as it were, universal-joint connection between the strip 9 and body 2 contributing to the last-mentioned ends.

20 It is obvious that changes may be made in the form and arrangement of parts comprising my invention without departing from the nature or spirit thereof.

Having thus described the nature of my improvements and explained a way of constructing and using the same, I declare that what I claim is—

As an improved article of manufacture, the herein-described improved truss, consisting of the flexible or spring body portion, a supporting-pad at one end thereof having a coil-spring connection therewith, and the hernial pad secured to its other end and consisting of a spiral spring having a pad secured to one end thereof, substantially as set forth. 35

In testimony whereof I have signed my name to this specification, in the presence of two subscribing witnesses, this 6th day of June, A. D. 1889.

MILTON HUTCHINS.
